UNITED STATES PATENT OFFICE.

GEORGE E. HIBBARD, OF CHICAGO, ILLINOIS.

ROTARY GAS-ENGINE.

SPECIFICATION forming part of Letters Patent No. 424,000, dated March 25, 1890.

Application filed July 12, 1887. Serial No. 244,050. (No model.)

To all whom it may concern:

Be it known that I, GEORGE E. HIBBARD, of Chicago, in the county of Cook and State of Illinois, have invented certain new and useful Improvements in Rotary Gas-Engines, of which the following is a description, reference being had to the accompanying drawings, forming a part of this specification, in which—

- 10 Figure 1 is an elevation representing what I term the "front" of the engine. Fig. 2 is a like view, in which certain of the parts are shown in vertical section and others broken away to show the interior mechanism. Fig. 15 3 is a transverse sectional view in plan upon the line *x* *x*, Fig. 2. Fig. 4 is a rear elevation or a view upon the opposite side from that shown in Fig. 1. Fig. 5 is an end view in detail showing the relative position of the 20 compression-tanks and air-pumps, a portion of the operating mechanism being omitted. Fig. 6 is a transverse sectional view in detail of a portion of one of the rotating disks, which serves as a temporary abutment or 25 cylinder-head, together with the shaft to which said disk is attached and the case by which the same is inclosed. Fig. 7 is a sectional view of a portion of said revolving disk, taken upon the line *y* *y*, Fig. 3. Fig. 8 30 is a vertical sectional view of the shell or cylinder and revolving disks, taken in the plane of the meeting flanges of said cylinder as viewed from the rear of the engine and in the direction indicated by the arrow shown 35 in Fig. 3; and, Fig. 9 is a front view, partly in section, showing a modification of the construction represented in the other figures, the compression-tanks being omitted therefrom.
- 40 Like letters of reference indicate like parts in the different figures.

My invention relates to gas-engines; and the objects aimed at in said invention are, first, to construct a rotary gas-engine so that 45 the piston may be rotated by means of the explosion of gas in the main cylinder without producing any violent or uneven movement of the engine-shaft; second, to provide means whereby the movement of the piston 50 may be initiated upon the admission of gas to the cylinder; third, to utilize the impact

of the explosion in pumping atmospheric air for mixing with the gas to form an explosive compound; fourth, to automatically govern the supply of air and gas to the cylinder in 55 proportion to the work to be accomplished; fifth, to provide mechanism for exploding the gas by means of electricity; sixth, to render said engine applicable to the use of illuminating-gas or that produced from hydrocarbon 60 oils; and, lastly, to render said engine reversible, all of which I accomplish substantially as hereinafter set forth and claimed.

I prefer to so construct said engine that it may be operated by means of gas generated 65 directly for its consumption within connecting apparatus or by illuminating-gas taken directly from the street-main; and as the latter may be employed with better results when passed through said apparatus than 70 when conveyed directly to the cylinder I have shown said engine in connection with said generating apparatus as the preferable form of construction, though I do not intend to confine myself thereto, for said apparatus 75 may be omitted with good results and without varying the more important features of my invention, as hereinafter shown and described.

Referring to the drawings, A represents the 80 frame of my improved engine, upon which is mounted an annular cylinder or shell B, which is formed in two parts bolted together by means of flanges *b* *b*', thus forming an interior annular chamber B', Figs. 3 and 8. 85

B², Fig. 3, represents a water-jacket surrounding said cylinder, having inlet and outlet pipes *b'* *b'*'.

C indicates the engine-shaft, which passes horizontally through the shell, as clearly 90 shown in Fig. 3. Upon said shaft is rigidly mounted a hub D, Figs. 3 and 8, to which in turn is attached a piston E, which is made to conform to the shape of the circular chamber B', and is preferably provided with two "follower-heads" E' E', though if the engine is not intended to be reversed one only is sufficient. The faces E² E²' of said follower-heads are of helicoidal form, as clearly shown in said last-named figures. I prefer to construct said 95 piston in one piece; but it is obvious that the follower-heads may be made separately and

attached thereto. The object of said helicoidal faces is to permit said piston to coact with notched disks or revolving abutments, as hereinafter stated. Diametrically opposite to each other with reference to the cylinder B, and arranged by preference in horizontal planes, are hollow disk-shaped casings F F', which are detachably secured by means of bolts f to similar casings F' F', which are integral with the cylinder and complete the connection therewith of the disks, Fig. 1, 2, 3, 4, 5, and 8.

Within the chambers formed by the parts F F', I place rotary disks, which consist of three plates G G G', Figs. 3, 6, 7, and 8. Said disks are riveted to each other, as shown at g, Fig. 6, and each has a sector cut therefrom, as shown by reference to Figs. 3 and 7. The disk G' is cut out more than those by which it is inclosed, and loose plates G² G³, Figs. 3 and 7, the faces of which are beveled, are provided to fill up said space. Slots g' g' are formed in said plates, through which are passed rivets g² g², which permit a sliding movement of said plates, which project normally beyond the respective faces of the plates G G, in which position they are retained by means of springs g³ g³. The respective disks formed by the three plates G G G' (which I designate generally as the disks G) are attached to vertical shafts G³ G³, which are mounted in suitable bearings formed upon the casings F F, as more clearly illustrated in Fig. 8. Said shafts are provided with beveled gears g⁴ g⁴, one being placed at the upper end of one and the other at the lower end of the other shaft. Into said gears respectively mesh correspondingly arranged shafts H H, Figs. 4 and 5, journaled in bearings H' H', attached to the shell B. Upon the opposite ends of the shafts H H are placed gears H² H², adapted to engage with a single gear C' upon the shaft C. The teeth of all of said gears are epicycloidal to prevent loss of motion, while each of the gears H² H² and C are irregular in form, a portion of the periphery of each being paraboloidal and the remainder concentric, whereby an accelerating motion is imparted through the shafts H H and G³ G³ to the revolving disks or abutments mounted within the casings F F, said disks being of such a diameter and so placed as to fully cover the opening in the main cylinder during the greater portion of the revolution of the disk. The plates G² G², forming the sides of the sector, are radial with the shaft G³, and one or the other of said plates is intended to sweep over and accurately fit the helical face of the follower-head, the spring g³ permitting a tight joint to be formed. So long as the engine runs in one direction but one follower-head is thus acted upon; but upon its reversal the other is brought into engagement with the sliding plate G² upon the opposite side of the sector. By means of the accelerating motion imparted to the gears the revolving disk is caused to pass

entirely across the chamber B while the piston is moving a distance represented by the length of the helical face E². Coincident with said passage of the piston the space in the cylinder behind is closed by the revolving disk, which forms an abutment to resist the explosion of the gas which thereupon takes place between said abutment and the piston, as hereinafter specified.

Within the plate G' are formed grooves g⁵, into which are placed insulated wires j j', Figs. 3, 6, and 4, which are broken at j', Fig. 3. Said wires are connected with projections j³ j³ upon the periphery of the disk G', which as the disk rotates are adapted to be brought into engagement with electrodes or contact-points J J, connected by wires J' J' with the respective poles of a dynamo-machine J², Fig. 4, the armature of which may be rotated by means of a belt driven by a pulley upon the shaft C.

J² J², Fig. 6, are metallic brushes secured in the ends of screws passing through the respective faces of the casing F and in the path of the point j', so that as the disk revolves the points are constantly brushed and kept clean. It will be observed that the points j³ j³ are so placed with reference to the electrodes J J as to form a contact therewith immediately after the passage of the plate G² over the face of the follower-head. Thus an electric spark is generated at j' at that time to produce the explosion of the gas in the cylinder.

Having thus described the cylinder and piston and the parts which coact directly with the latter, I will now describe the mechanism for introducing the gas and air and for exhausting their products when exploded.

Arranged upon opposite sides of and rigidly attached to the cases F F are compression-cylinders K K' K² K³, each of which is provided with a stop-valve k, whereby air may be compressed in said cylinders, respectively, as desired. Ports or ways K⁵, Figs. 2 and 8, form a means of communication between the cylinders K K' K² K³ and the chamber B'. Attached in turn to the ends of said respective cylinders are air-pumps L L' L² L³, each of which is provided with a piston l, connected by a piston-rod k' to a piston K⁴ within the compression-cylinder, to which said air-pumps are respectively attached, as clearly shown at the left in Fig. 2. Each air-pump is provided with a valve l', communicating with a gas-pipe l', connected with a street-main and an opening l, by which atmospheric air is admitted to said pump; also, communicating with said respective pump-cylinders are pipes M, M', M², and M³. The pipe M communicates directly with a carbureting-tank N, passing into the top of said tank and downwardly through the same, as shown in Fig. 2, to a point near the bottom, where it passes through a perforated plate N', Fig. 2. The tank N is connected with a secondary compression-tank N² by means of a pipe N³ at the top. The three

- 5 pipes M' , M^2 , and M^3 are "collected," as shown in Fig. 4, and all communicate directly with the pipe M . When the engine is not to be operated by means of ordinary illuminating-gas, the tank N is designed to be filled with naphtha for the purpose of carbureting the air which is pumped therein, and a cock n is therefore provided for the purpose of withdrawing said naphtha when desired.
- 10 O is a pipe which communicates with the compression-tank N^2 , and connects in turn with a two-way cock P , Figs. 1 and 2, with which are connected pipes O' O^2 , leading to ports o o' , Fig. 8, in the cylinder B . Branch pipes O^3 O^4 lead from said pipes O' O^2 , respectively, to ports o^2 o^3 , one of which is shown in full and the other indicated in dotted lines in Fig. 8. The ports o o' and o^2 o^3 serve, respectively, as induction or exduction ports, according to the direction in which the piston is rotated. When revolved as indicated by the arrow in Fig. 8, the ports o and o' are the induction-ports. Interposed in the pipes $O' O^2 O^3 O^4$ are rotary stop-valves p p' p^2 p^3 , Fig. 2, to which are attached rigid arms p^4 , Figs. 1 and 3, which are in turn loosely pivoted to sliding rods P' P^2 P^3 P^4 , provided with friction-rollers p^5 upon their respective ends.
- 15 O^5 is an exhaust-pipe which connects with the cock P upon the opposite side from the pipe O . Said exhaust-pipe is preferably carried upwardly in a spiral form through the tank N , as shown in Fig. 2, for the purpose of raising the temperature in said tank; but it is obvious that it may serve equally well as a simple exhaust without such extension.
- 20 The arms $P' P^2 P^3 P^4$ are loosely mounted in brackets P^5 , Fig. 3, and are arranged to slide longitudinally in their respective bearings.
- 25 A segment Q , Fig. 1, is mounted upon projecting studs q q' , which are attached rigidly to the frame, said segment having slots q' q' formed therein to permit a circular sliding movement thereof upon said studs. A rack q^2 upon said segment is engaged by a corresponding gear r upon the end of a throttle-valve lever R , which is attached to and serves to actuate the two-way valve P . A notched segment R' and spring-catch r' serve to retain the lever in any desired position. The sliding segment Q is provided with inclined planes q^3 q^4 upon its respective ends, which serve to engage the friction-rollers p^5 , and thus in a measure regulate the position of the slides P' P^2 P^3 P^4 , which are caused to slide inwardly toward the shaft C by means of springs q^5 q^6 , Fig. 3.
- 30 Keyed to the shaft C is a fly-wheel C' , Fig. 3, between which and the engine-cylinder I provide a cone-shaped eccentric collar C^2 , which is adjusted to move longitudinally upon said shaft, and against which the inner ends of two of the sliding rods normally abut, the other two being held outwardly therefrom by the inclined planes q^3 q^4 of the segment Q .

The spline c causes said collar to revolve with the shaft.

C^3 C^4 are cylinders having guide-rods c' c'' , loosely fitted in radial bores formed within the hub of the wheel C' . Pistons c^2 c^3 , attached to piston-rods c^3 c^4 , which are rigidly secured to the rim of the fly-wheel, as shown, are inserted within the outer ends, respectively, of said cylinders. Pipes c^4 c^4 , having stop-valves, are provided for forcing compressed air into said cylinders, so that they normally retain the positions shown in the drawings when the fly-wheel is at rest. Pivoted at c^5 upon the brackets C^4 , attached to the fly-wheel, are bell-crank levers C^6 , the long arms of each of which are loosely fitted within a groove formed in the collar C^2 , while the short arms are fitted by means of ball-joints in sockets formed in the cylinders C^3 C^4 . The longitudinal movement of said cylinders is thus communicated to the collar C^2 , which is thereby caused to move back and forth upon the shaft C . This in turn modifies the movement of the sliding arms P' P^4 or P^2 P^3 , as the case may be, and thus governs the supply of gas to the engine-cylinder, as hereinafter more fully explained.

I have now described the respective parts of said engine as I prefer to construct it for general use. I will now explain its operation.

Assuming the cylinders K K' K^2 K^3 to be charged with compressed air at a pressure of, say, two atmospheres, or such a degree in proportion to the size of the engine as may be found to be most desirable, and assuming the tank N^2 to be filled with air at about the same pressure and the tank N to be filled with naphtha, and assuming the lever R to be moved from a vertical position to that shown in Fig. 1, which causes the main or throttle valve P to assume the position shown in Fig. 2, the compressed air and gas from said tank is permitted to enter the cylinder B , where it exerts a sufficient force upon the piston E to cause it to rotate, as indicated by the arrow in Fig. 8. When it has revolved sufficiently to cause the dynamo J^2 to generate a current of electricity, and the disk G , immediately behind the piston, is in such a position that the contact-points j^3 j^4 are brought into contact with the electrodes J J' , (at which time the disk G will have wholly closed the cylinder B behind the piston, thereby forming an abutment or partition,) an electric spark is generated at j^2 , (see lower part of Fig. 3,) and an explosion takes place between the piston and abutment. To prevent injury from the violence of the explosion and to impart an even and uniform movement to the piston E , communication is established between the engine-cylinder and compression-cylinders by means of the ports K^5 , Figs. 2 and 8. This permits the force of the explosion to act upon the piston K^4 in the compression-cylinder, which is driven against the compressed air confined therein, thereby forming an elastic

cushion, which reacts upon the piston and forces the gas back into the main cylinder to drive the piston E. The movement of the piston K⁴ actuates the air-pump, driving the piston l upwardly and forcing the air from its chamber into the pipe M, its return being prevented by means of the check-valve m; Fig. 2. The reverse movement of the piston l, caused by the reaction of the compressed air in the chamber K, draws in a volume of air through the valve E. This action is repeated with each half-revolution of the piston E, the gears shown in Fig. 4 being so adjusted as to cause one or the other of the plates G² to sweep one of the faces E² of the piston E, forming a close joint therewith, and the contact-points³ are so arranged as to close the circuit with the poles of the dynamo the instant this action takes place, and thus produce an explosion. It will be observed by reference to Fig. 1 that the sliding arms P² P³ are held in extreme abnormal positions by the faces q³ q⁴ of the segmental plate q. This causes the valves p' p² to remain open so long as the segment remains in such position, thereby retaining the ports o' o², Fig. 8, open, during which time they act as exhaust-ports, while o o² serve as admission-ports, respectively. The latter are alternately opened and closed by means of the eccentric C³, as clearly shown in Fig. 1. The extent to which they may be opened is governed by the speed of the engine and the work to be performed. When the work is light and the speed becomes too great, the centrifugal force of the cylinders C³ overcomes the resistance of the compressed air within said cylinders, and they move away from the center, and thus by the action of the levers C⁵ draw the collar C² nearer to the fly-wheel, thus causing the ends of the sliding arms P' P¹ to be brought into contact with the inclined face of said eccentric, which serves to but partially open the valves with which they are connected. When running in the direction indicated, the pipes O³ O' serve as the admission-pipes, while the exhaust is through the pipes O² O¹. The cylinders K K' and air-pumps L L' are likewise employed at this time, the others being idle. Upon reversing the lever R the cylinders K² K³ and pumps L² L³ are brought into operation and the pipes O³ O¹ become the admission-pipes and O² O³ the exhaust-pipes. The heat from the exhaust-pipe, which is carried through the tank N, heats the naphtha in said tank, and the air which enters through the pipe M and passes upwardly through the perforated plate N' becomes highly charged with hydro-carbon and passes into the tank N² as an explosive compound.

It is obvious that when ordinary illuminating-gas is employed the carbureting-tank N may be dispensed with; nor is it necessary to employ the compression-tank N¹ except to store the pneumatic power for starting the engine. Fig. 9 shows a modification of the

construction represented in the other figures, designed for the use of street-gas only. It will be seen that the pipe M is carried directly to the pipe O, the air and gas being drawn in by the respective air-pumps, all of which communicate with said pipe O. In this form it is necessary to start the engine by rotating the fly-wheel before it will propel itself; but where the tanks N N² are employed and it is desirable to use street-gas the gas-line may be withdrawn from the tank N, when air and illuminating-gas may be pumped in without further change. The heating of the gas and air by means of the exhaust-pipe O⁵ is a considerable advantage, and this fact, coupled with the facility with which the engine may be adapted to the use of either form of gas when the tanks N N² are employed, and the fact that it may be started by merely opening the throttle-valve, renders the use of the said tanks desirable.

I do not confine myself to the special form of rotating disks in the main cylinder for creating abutments to resist the explosion, as it is obvious that other means may be employed for that purpose—for example, the sliding abutments shown in my patent, No. 282,520, of August 7, 1883.

By increasing the number of air-pumps and compression-chambers and connecting them with the main cylinder and providing additional abutments and exhaust and governing mechanism it is obvious that the number of explosions may be increased for each cycle of the piston, thereby enabling the power of the engine to be increased indefinitely. This is a great advantage in engines of this class. A further advantage is that the revolving disks cut off the exploded gas from the chamber into which the next succeeding explosion is to occur.

Having thus described my invention, I claim—

1. In a gas-engine, the combination of a rotating piston having a follower-head of helicoidal form, one or more rotating disks arranged to sweep the face of said follower-head and form an abutment behind it, wires electrically connected with a source of electricity and arranged to complete the circuit and produce an electric spark upon forming the abutment behind said cylinder, and means for introducing an explosive gas to the cylinder, substantially as shown and described.

2. In a gas-engine, the combination of a cylinder, a rotating piston having a helical-faced follower-head, a rotating disk notched radially from its axis and arranged to pass immediately in the rear of and form an abutment behind said cylinder during its rotation, and means, as irregular gears, connecting with the main shaft for imparting an accelerating motion to said disk, substantially as shown and described.

3. The combination, with the main cylinder and piston of a gas-engine, of a compression-

- 5 cylinder and air-pump, each having a separate piston but connected by a common piston rod, means, as described, for injecting a volume of compressed air upon one side of the piston in the compression-cylinder, a port upon the opposite side of the piston leading to the main cylinder, a pipe connecting the air-pump with the throttle-valve, and means, as specified, for introducing air and gas to said air-pump, whereby the impact of the explosion may be cushioned and at the same time utilized for pumping air and gas to the engine, substantially as shown and described.
4. The combination, with the cylinder, rotating piston, and abutments of a gas-engine, and means, as set forth, for producing an electric spark in said cylinder, of a compression-cylinder and an air-pump having connected pistons, ports, or ways between the main and compression cylinders, and a storage or compression tank connected with said air-pump and with the throttle-valve, substantially as shown and described.
5. The combination, with the cylinder, rotating piston, and abutments of a gas-engine, and means, as specified, for producing an explosion of gas in said cylinder, of a compression-cylinder and air-pump having connected pistons, ports, or ways between the main and compression cylinders, and a carbureting and storage tank communicating with each other and with the air-pump and throttle-valve, respectively, substantially as shown and described.
- 35 6. The combination, with the main cylinder, rotating piston, and abutments of a gas-engine, and means, as specified, for producing an explosion of gas in said cylinder, of two or more compression-cylinders, as K K', communicating with said main cylinder, a corresponding number of air-pumps having their pistons respectively connected with pistons in said compression-chambers, means for introducing air and gas into said pumps and for connecting the latter to the throttle-valve, admission and exhaust ports, and mechanism for controlling the admission of the air and gas to the former, substantially as shown and described.
7. In a rotary gas-engine, the combination of a helical-faced piston, notched rotating

disks arranged in planes radial to the axis of the cylinder, and eccentric gear for imparting an accelerating motion to said disks, substantially as shown and described.

8. In a rotary gas-engine, the combination, with a helical-faced piston, of rotating notched disks arranged in planes radial to the axis of the piston and provided with sliding plates G² and springs g³, substantially as shown and described.

9. The combination of the helical-faced piston E, rotating disks G G', having sliding plates G², wires g⁵ g⁶, having contact-points j³ j³, electrodes J J, and electrical connections with a source of electricity, substantially as shown and described.

10. The combination, with the main cylinder, rotating piston, and abutments of a gas-engine, and means, as specified, for producing an explosion of gas in said cylinder, of a series of compression-cylinders communicating with said main cylinder, a series of air-pumps having their pistons connected, respectively, with pistons in said compression-cylinders, means, as specified, for introducing air and gas into the main cylinder by means of said pumps, a two-way throttle-valve, admission and exhaust ports, and means, as specified, for governing the admission of said air and gas to the admission-ports, whereby said engine may be reversed and run in opposite directions, substantially as shown and described.

11. The combination, with the admission-valves of a gas-engine, of the cylinders C³, loosely attached to the fly-wheel and held normally against the hub by means of compressed air therein, an eccentric collar loosely mounted upon the engine-shaft and connected with said pistons by means of bell-crank levers, and in operative connection with said valves by means of arms and sliding rods, and means for holding said rods against the face of said eccentric, whereby said valves are opened more or less in proportion to the speed of the engine and the work to be done thereby, substantially as shown and described.

GEORGE E. HIBBARD.
